UNITED STATES PATENT OFFICE

JAMES F. DORAN, OF DANBURY, CONNECTICUT; JOHN C. DORAN EXECUTOR OF SAID
JAMES F. DORAN, DECEASED

HAT IRONING MACHINE AND THE LIKE

Application filed November 5, 1926. Serial No. 146,401.

This invention relates to hat making or hat finishing apparatus and more particularly to a machine for performing upon hats an operation such as ironing the crowns thereof, 5 or the like.

One of the objects of the invention is to provide a machine of the above nature which is highly efficient and adaptable to a wide range of use. Another object is to provide 10 a machine of the above nature which is capable of a high production. Another object is to provide a machine of the above nature which is compact and economical of floor space and convenient to operate. Another 15 object is to provide a machine of the above nature which effects a saving in the power required to drive the various operating mechanisms. Another object is to provide a machine in which a plurality of hats may 20 be operated upon simultaneously. Another object is to provide a machine of the above nature which is simple and inexpensive to build. Other objects will be in part obvious or in part pointed out hereinafter.

25 The invention accordingly consists in the features of construction, combinations of elements, and arrangements of parts as will be exemplified in the structure to be hereinafter described and the scope of the application of 30 which will be indicated in the following claims.

In the accompanying drawings in which is shown one of the various possible embodiments of this invention,

35 Figure 1 is a top plan view of the machine, various parts thereof being shown in section;

Figure 2 is a section taken substantially along the line 2—2 of Figure 1;

40 Figure 3 is a section taken substantially along the line 3—3 of Figure 2;

Figure 4 is a section taken substantially along the line 4—4 of Figure 1;

Figure 5 is a section taken substantially along the line 5—5 of Figure 4;

45 Figure 6 is a detail view of an adjustment;

Figure 7 is a section taken substantially along the line 7—7 of Figure 4, and

50 Figure 8 is a section taken substantially along the line 8—8 of Figure 4.

Similar reference characters refer to similar parts throughout the several views of the drawings.

Referring now to Figures 1 and 2 of the drawings in detail, there is shown a base 10 which may be of any suitable construction, being preferably mounted upon legs 11 so as to be positioned at a convenient height from the floor. Upon the upper surface of this base 10 is an upright frame 12 which carries four bearings 13, 14, 15 and 16, these bearings being spaced preferably substantially 90°. In these four bearings of the frame 12 are rotatably supported four shafts 17, 18, 19 and 20 respectively, these shafts 60 projecting outwardly respectively toward the four sides of the frame and their inner ends approaching substantially at the center of the machine. The shafts 18, 19 and 20 are shown as having at their outer ends means 65 for supporting hat blocks, the three blocks with hats thereon being shown at 21, 22 and 23 in Figure 1. These hat block supporting devices will be described in detail later.

Adjacent their inner ends, the shafts 17, 18, 19 and 20 have secured thereto beveled gears 24, 25, 26 and 27 respectively. These four beveled gears mesh with a single gear 28 which is shown clearly in Figure 2. This gear 28 is secured upon a shaft 29 which is rotatably carried in a bracket 30 arching between the two bearings 13 and 15. Preferably, this shaft 29 carries at its upper end a beveled gear 31 by which it may be driven through a beveled gear 32. The gear 32 is secured upon a shaft 33 carried in a bracket 34 and having at its end opposite the gear 32 a pulley 35 or other power connection by means of which it may be rotated. From the description thus far, it will be seen that 30 the four shafts 17, 18, 19 and 20 may be driven from a belt or other suitable power connection to the shaft 33, the drive taking place from the shaft 33 to the gear 32, gear 31, shaft 29, gear 28, and the respective gears 24, 25, 26 and 27.

In the embodiment of this machine shown in the drawings, the shaft 17 is not provided with means for supporting a hat block as are the shafts 18, 19 and 20. It will be ready-

ly understood, however, that the shaft 17 may be equipped as are the other three shafts, thereby making provision for supporting and rotating four hat blocks instead of three, all four shafts being rotated by the drive above described.

In the embodiment shown in the drawings, there is mounted, upon what will be termed the back side of the machine, an electric motor 36 which is connected to drive the shaft 17. The drive may be through any suitable type of speed reduction mechanism and is shown herein as comprising a worm 37 mounted upon the armature shaft of the motor 36 and driving a worm wheel 38 which is secured to the shaft 17 adjacent its outer end. This speed reduction is adapted to effect from the motor 36 a drive of the shafts 18, 19 and 20 at a speed suitably slow for rotating the hat blocks as the work is performed upon the hats. When the machine is driven from the motor 36 it will be seen that the drive is effected from the shaft 17 through the gear 24 to the gear 28 and from the gear 28 to the gears 25, 26 and 27 to rotate the respective shafts 18, 19 and 20.

It will be seen that the direction of rotation of the shaft 17 is opposite to that of the shaft 19, and that the direction of rotation of the shaft 18 is opposite to that of the shaft 20. This is true whether the drive of the machine be from the motor 36 or from the pulley 35. The result is that each of the hat blocks, as viewed from the front thereof, rotates in the same direction, this direction being preferably clockwise. This is important in a hat ironing machine since it is necessary that all the fibers of the fur be laid in the same predetermined direction. The hat surface must move across the iron in such direction that the ironing action acts with the so-called "lay" of the fur fibers. In the machine herein disclosed each of the several hats moves by the operating tool, in this case an iron, in the same direction and in the proper direction to accommodate the original lay of the fur fibers.

As shown in Figure 2 and also in Figure 5, the inner ends of the shafts 17 and 19 may approach closely and their ends may be recessed axially to receive a cylindrical pin 39. This pin is received loosely in the shaft recesses and serves to steady the two shafts. It does not form a driving connection between the shafts 17 and 19, however, since, as above pointed out, these two shafts are driven in opposite directions.

Considering now the mounting of the hat blocks 21, 22 and 23 upon the outer ends of the shafts 18, 19 and 20, respectively, one of these mountings only need be described in detail, since they are preferably all identical. Referring to Figure 2, the hat block 22, which is ordinarily formed of wood, is provided with a hub 22a in which is a central

recess 22b. The outer end 19a of the shaft 19 enters the recess 22b and centers the hat block for rotation. Positioned upon the shaft is a face plate 40 against which the base of the hat block ordinarily rests when the hat block is placed in position. A suitable device is provided for gripping the hub 22a of the hat block to hold the block firmly in position while the hat is being operated upon. In the embodiment shown in the drawings there are provided jaws 41 having deeply knurled gripping surfaces capable of taking a firm hold upon the surface of the hub 22a. These jaws protrude through radial slots in the face plate 40 and are connected by a toggle linkage 42 with a collar 43. The collar 43 is threaded upon the shaft 19 and is provided with a suitable handle taking the form of a wheel 44 by means of which it may be threaded along the shaft toward and away from the face plate 40. By turning the wheel 44 in a counter clockwise direction the jaws 41 are moved together to firmly grip the hat block, and by turning the handle in the opposite direction the hat block is released. The shaft 19 rotates but slowly and the hat blocks may be placed in position or removed while the shaft continues to rotate.

Adjacent to each of the hat block supporting devices is mounted a tool which is adapted to operate upon the hat carried by the hat block, and to move across or traverse the surface of the rotating hat. The tools shown herein are ironing tools adapted to iron the crowns of the felt hats against the blocks upon which they are supported. In the manufacture of felt hats it is the usual practice to bring the crown of the hat to shape and size by stretching the hat body tightly over the hat block, the felt being first softened by the application of steam. The hat is then secured to the block as by a cord drawn tightly around the band, and thereafter the ironing of the hat crown is performed. The felt is moistened and a heated iron is traversed over the surface thereof. The heat and pressure of the iron dries out the felt and has a tightening and felting action upon the fur fibers, causing them to enter into tighter union; at the same time the hat is tightly shrunk to the size and shape of the block and the felt is strengthened so that when the hat is subsequently removed from the block it retains its shape and size.

Referring again to the drawings, there is shown in Figure 4 an ironing tool 45 adapted to bear against and traverse over the surface of a hat carried by the hat block 21, and in Figure 1 there is shown an ironing tool 46 for the block 22 and an ironing tool 47 for the block 23. The ironing tools are traversed across the surfaces of the respective rotating hats in a path of movement extending from the band to the tip of the

hat or, if desired, from the band on one side through the tip to the band on the opposite side. The ironing tools of this machine move in a horizontal plane about the hat, and the mechanism for effecting this traversing movement of the tools will presently be described in detail. In the drawings, each of the irons 45, 46 and 47 is shown drawn back out of engagement with the hats. The two irons 45 and 46 are shown in substantially the same position with respect to their respective hats while, for the sake of convenience in making the drawings, the iron 47 is shown at a different position in its path of traverse.

Referring now to Figures 2 and 4, within the frame structure 12 and beneath the inner end of the shaft 17, is positioned a worm wheel 48 which meshes with a worm 49. This worm 49 is secured to the shaft 17 and hence driven therefrom, thus effecting rotation of the worm wheel 48 at reduced speed. As shown in Figures 2 and 5, the worm 49 is preferably supported in part by the shaft 19, the shaft 19 entering freely into the hub of the worm. The worm gear thus aids in supporting the inner ends of the two shafts 17 and 19, thereby strengthening the structure, and at the same time the worm gear is provided with a firm mounting to withstand the driving thrust occasioned by its drive to the worm wheel 48.

Secured to the worm wheel 48 is a link or crank 50 which is pivotally connected at 51 with an upstanding bracket 52. This bracket 52 is adjustably secured by set screws 53 to a slideable rack 54. It will be seen that as the worm wheel 48 is slowly rotated, the rack 54 is reciprocated by the link or crank 50 and its connection with the rack by the bracket 52. The worm wheel is provided with a counter weight 55 for the purpose of preventing the wheel from stopping in such position that the crank 50 is on dead center.

The connection between the crank 50 and the worm wheel 48 is formed by a bolt 56 passing through a radial slot 57 in the worm wheel, as shown in Figure 2. By adjusting the bolt 56 in the slot 57 toward and away from the center of the worm wheel, the length of the reciprocations imparted to the rack 54 may be adjusted. In Figure 4 the worm wheel is shown in a different angular position to more clearly show the bolt 56 and the slot 57. As shown in this figure, there is preferably provided on the worm wheel 48 a screw 58 to facilitate making adjustments of the connection between the crank and the worm wheel and to lock the parts in the position to which they are adjusted. This screw 58 passes through a lug 48a on the worm wheel and engages the surface of a collar 59 which is positioned about the bolt 56 between the worm wheel and the crank 50.

The worm wheel 48 is rotatably mounted

and carried in an arm 60 which is pivoted at one end in the frame 12, as shown at 61 in Figure 2. This arm 60 may be swung about the pivot 61 to move the worm wheel downwardly out of engagement with the worm gear 49, thereby to interrupt the drive of the rack 54. The arm 60 at its end opposite from the pivot 61 is supported by a part 62, this part 62 being carried in a depending member 63 and being vertically adjustable therein by an adjusting screw 64. These parts are shown in Figure 2 and in Figure 3. The member 63 is swiveled at its upper end on an eccentric 65 of a part 66 which is rotatably mounted in the frame 12 just beneath the bearing 15. This part 66 is provided with a handle 67 by means of which it may be rotated to turn the eccentric 65 and raise or lower the member 63. Thus by operating the handle 67 the member 63 may be lowered to permit the worm wheel 48 to drop out of engagement with the worm gear 49, thereby to interrupt the drive of the rack 54. The screw 64 is adjusted to such a point that, when the member 63 is raised by the eccentric, the worm wheel is in proper driving engagement with the worm gear.

The reciprocating rack 54 is connected to effect the traverse of the iron 46 across the surface of the rotating hat on the block 22 by mechanism which will be described presently, this drive being imparted to the iron by the rack teeth 54a adjacent the outer end of the rack. As may be seen in Figure 1, the rack 54 is provided with another toothed portion 54b adjacent the middle part thereof, these teeth 54b being formed upon the side of the rack opposite to the teeth 54a. These teeth 54b are in engagement with and are adapted to rotate a gear 68 which is freely mounted upon an upright stud shaft 69 projecting from the base 10. Also in engagement with this gear 68 is a slideable rack 70 which extends at right angles to the rack 54. This rack 70 is shown more clearly in Figure 4.

As the rack 54 is reciprocated by the worm wheel 48 and crank 50, it turns the gear 68 and thereby effects reciprocation of the rack 70 in a horizontal path at right angles to the horizontal path of reciprocation of the rack 54. The rack 70 is adapted, through connections which will be described, to impart the traversing movement of the two ironing tools 45 and 47.

As is shown in Figures 1 and 2, the ironing tool 46 is supported, by a construction which will be described, at the outer end of an arm 71. This arm 71 is swiveled at its inner end about a vertical axis in a bracket 72 extending outwardly from the frame 10 beneath the hat block 22. Preferably the arm 71 is provided with a downwardly extending spindle 73 which is suitably supported by anti-friction means in the bracket 72. The arm 71

105

110

115

120

125

130

is also provided with a gear 74 which meshes with the teeth 54a of the rack 54. Thus, as the rack 54 is reciprocated by the crank, the arm 71 is swung about the axis of the spindle 73, and this movement effects the traverse of the ironing tool 46 across the hat surface, as will be described.

In similar manner, as shown best in Figure 4, the ironing tool 47 is carried at the outer end of an arm 75 which is swiveled in a bracket 76, and the ironing tool 45 is carried at the outer end of an arm 77 which is swiveled in a bracket 78. Also, the arm 75 is provided with a gear 79 similar to the gear 74 of the arm 71, and the arm 77 is provided with a similar gear 80.

As shown in Figure 4, the gear 79 is engaged by a rack 81 and the gear 80 is engaged by a rack 82. These two racks 81 and 82 are adjustably secured to the rack 70 by bolts 83 and 84 respectively. These bolts are secured in the rack 70 and pass through slots in the respective racks 81 and 82. Thus, as the rack 70 is reciprocated, the arms 75 and 77 are turned in their swiveled mountings to effect the traverse of the respective tools 47 and 45 across the surfaces of the hats carried by the hat blocks 23 and 21. The adjustable connections between the rack 70 and the racks 81 and 82 permit independent adjustment of the motion imparted to the ironing tools 45 and 47 by the reciprocations of the rack 70.

From the foregoing it will be seen that the three ironing tools 45, 46 and 47 are given their traversing movements from the central driving means embodied in the worm wheel 48 and the crank 50. The rack 54 which effects the traversing movement of the tool 46 is driven directly from the crank 50. The reciprocations of this rack 54, through the gear 68, effect reciprocation of the rack 70 which, through the racks 81 and 82 connected thereto, effect the traversing movements of the tools 47 and 45. It will be seen that this arrangement is exceedingly simple and compact and of great advantage in that a number of hats may be operated upon at one time with a minimum expenditure of floor space. Also the machine is so arranged that it is attended by the operator with the greatest convenience and efficiency.

The mountings of the ironing tools 45, 46 and 47 at the outer ends of the respective arms 77, 71 and 75 are preferably substantially identical so that one only need be described in detail, similar reference characters being applied to similar parts in the drawings. Considering the structure at the outer end of the arm 71, for example, referring to Figure 1, there is swiveled at 85 a horizontal arm 86. Adjacent the outer end of this arm 86 the iron 46 is carried. The arm 86 is urged to swing inwardly toward the hat about its pivot 85 by suitable means act-

ing through a cable 87. The arm is shown held away from the hat against the action of the cable 87, the iron 46 being thus in an inoperative position. The iron is held in this inoperative position, when not in use, by a vertical pin 88 which is carried in a lug 89 formed on the lever 86. In the end portion 71a of the arm 71 is provided a hole into which this pin drops by gravity or other suitable means to hold the parts in the position shown in the drawings. A handle 90 is provided by means of which the arm 86 may be swung about its pivot 85. To move the iron into engagement with the hat, the pin 88 is lifted from engagement with the hole in the part 71a, and the pull of the cable 87 then swings the iron about the pivot 85 into engagement with the surface of the hat.

The mounting of one of the irons upon the end portion of its lever 86 is best shown in Figure 4, the iron here shown being the iron 45. Referring to this figure, clamped in a bracket 86a of the arm 86 is an upright member 91 which preferably takes the form of a hollow pipe through which electric wiring 92 may be passed to supply energy for heating the iron. The iron is carried directly by an upright member 93 to which the iron is swiveled by a horizontal pin 94. This upright member 93 is swiveled at its lower end in the end portion of the arm 86, and at its upper end it is supported to turn freely in a bracket 95 carried at the upper end of the pipe 91. The iron 45 is permitted to swivel about the horizontal axis of the pin 94 as it traverses the surface of the oval hat. Because of this swiveling and also the swiveling about the vertical axis of the part 93, the iron is permitted to accommodate itself to the curves of the oval hat. In order to keep the iron 45 normally in an upright position and to prevent the weight of the iron from causing it to swing over at an angle about its pivot 94, there is provided an adjustable compression spring 96 which yieldingly bears against the rear surface of the iron beneath the pivot 94.

In Figure 4 there is shown clearly the cable 87 by which the iron is urged to swing about the pivot 85 and bear against the surface of the hat. This cable is shown as passing around a roller 97 which is mounted upon a vertical pin adjacent to the pivot of the arm 77. After passing around the roller 97, the cable passes over a roller 98 and thence downwardly through the hollow spindle 73. The cable supports at its lower end (not shown) suitable weights which may be removable and interchangeable to vary the pressure with which the iron is urged against the hat. The rollers 97 and 98 permit the cable to operate freely without friction, and they properly guide the cable at all positions of the arm 77 as it swivels in its bearing.

The cable 87 acts upon the iron through a

member 99 which is adjustably secured to the upright part 93 by a set screw 100. This member 99 is provided with a plurality of radially projecting fingers 101, 102 and 103, these fingers being shaped to receive a knot in the end of the cable 87. The cable is shown in Figure 4 as connected to the finger 103. By adjusting the member 99 about the axis of the part 93, the cable is made to act upon the part 93 through an arm of force which tends to tip the iron about the axis of the part 93 in one direction or another as the iron operates upon the side portions or upon the "square" of the hat. The fingers 101, 102 and 103 are of different lengths so that the arm of force may be varied by employing different fingers, and the tilting tendency may be correspondingly increased. This tilting of the iron is important in enabling the iron to operate effectively close up to the band of the hat, and it also prevents a sudden swinging or jumping of the iron over the square of the hat.

The purpose of the adjustment between the crank 50 and the worm wheel 48 will now be more apparent. By varying this connection by means of the bolt 56 in the slot of the worm wheel, the length of reciprocations of the racks is determined and hence the lengths of the paths of movement of the several irons over the hats. This adjustment may be made such that irons will travel from the band of the hat on one side, across the tip and to the band on the other side; or the adjustment may be made such that the iron travels between any two intermediate points. Moreover, it will be seen that this one adjustment between the worm wheel and the crank determines the path of movement of all of the ironing tools.

The adjustment of the bracket 52 along the rack 54 makes it possible to adjust the starting point of the traverse movement of the iron and hence the locus of the traverse for any given length thereof. Ordinarily the traverse is started at the band. In some cases it is desirable that the iron traverse from the band to the tip and then return to its starting point, while in other cases it is desirable that the iron traverse from the band on one side to the band on the other side and return. It will be seen that the machine is adjustable to meet varying requirements. In addition to these adjustments just discussed, the adjustable connections between the rack 70 and the racks 81 and 82 make it possible to adjust the locus of the traverse of the two tools 45 and 47 independently of each other and independently of the tool 46.

As shown in Figure 4 and in Figure 7, there is provided in each of the face plates 40 a projecting pin 105 which takes into a recess 104 of the hat block, this pin determining the angular positions of the major and minor

axes of the hat block. The recess 104 is positioned on the line of the major axis. As shown in Figure 7, the face plate 40 is provided with a plurality of threaded openings 106 each of which is capable of receiving the threaded pin 105.

As the hats are being ironed, the iron is preferably urged against the hat block with considerable pressure. When the iron is operating upon the sides of the hat, as the ends of the hat approach the iron the hat is required to force the iron outwardly, and as the ends recede from the iron the iron moves inwardly and tends to assist the rotation of the hat instead of impeding it. By adjusting the pins 105 on the respective face plates the rotation of the several hats in this machine may be so related that while the rotation of one hat is impeded because of exerting pressure to force the iron outwardly, the rotation of another hat is aided by reason of the iron acting thereon. In other words, the several hat blocks are so adjusted that no two hats are required to force their irons outwardly at the same time. Since the several shafts upon which the hats are mounted are all geared together, the aid given to rotation by one iron helps to rotate the other hat or hats which may be at that moment required to force their irons outwardly. In this manner the operation of the machine is made smoother and more even and the power required to rotate the several hat blocks is very appreciably reduced.

From the foregoing it will be seen that there is herein provided a machine which achieves the objects of this invention and accomplishes results of obvious practical value. A maximum amount of work is accomplished with greatest efficiency, the floor space required being cut to a minimum, the power employed in driving the machine being most efficiently used and the machine as a whole being arranged for convenient and efficient attendance by the operator.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim as my invention:

1. In a machine of the character described, in combination, a frame, a plurality of devices for rotatably supporting hat blocks positioned at angularly spaced points on said frame, a plurality of tools, one adjacent to each of said hat blocks, a driven shaft, means driven from said shaft adapted to rotate said hat blocks, a wheel driven from said shaft, a crank driven from said wheel, a rack reciprocated by said crank and connected to move one of said tools across the surface of the rotating hat block adjacent thereto, and

other reciprocating racks angularly disposed with respect to said first rack and driven from said first rack adapted to move said other tools.

5. 2. In a machine of the character described, in combination, a frame, a plurality of devices for rotatably supporting hat blocks positioned at angularly spaced points about said frame, driving means for rotating all 10 of said devices a plurality of tools, one adjacent to each of said hat blocks, means for rotating said hat blocks all in the same direction relative to the respective tools, angularly disposed means adapted to move each 15 of said tools back and forth in a path of traverse across the surface of the rotating hat block adjacent thereto, and a single adjustment for adjusting the lengths of the paths of traverse of all of said tools.

20. 3. In a machine of the character described, in combination, a frame, a plurality of devices for rotatably supporting hat blocks positioned at spaced points about said frame, a plurality of tools, one adjacent to each of 25 said hat blocks, means for rotating said hat blocks all in the same direction relative to the respective tools, means adapted to move each of said tools back and forth in a path of traverse across the surface of the rotating hat 30 block adjacent thereto, and means for adjusting simultaneously the loci of the traverses of all of said tools.

4. In a machine of the character described, in combination, a frame, a plurality of devices for rotatably supporting hat blocks positioned at spaced points about said frame, a plurality of tools, one adjacent to each of 35 said hat blocks, means for rotating said hat blocks in a clockwise direction relative to the respective tools, means adapted to move each 40 of said tools back and forth in a path of traverse across the surface of the rotating hat block adjacent thereto, and means for adjusting the locus of the traverse of one of said tools independently of the locus of the traverse of another of said tools.

5. In a machine of the character described, in combination, a plurality of devices for supporting oval hat blocks, means for rotat- 50 ing said hat blocks, a plurality of irons adapted to iron the crowns of hats carried by said rotating hat blocks, one iron being provided for each hat block, means for rotating said hat blocks and means for yield- 55 ingly holding each of said irons inwardly toward its respective hat block, and means for determining the angular relation between said hat blocks whereby when a side portion of one thereof is moving toward its iron a side portion of another is moving away from its iron.

6. In a machine of the character described, in combination, a plurality of shafts, a plurality of devices for supporting oval hat 60 blocks, one of said devices being positioned at

the end portion of each of said shafts to be rotated thereby, a common driving means for rotating said shafts, a plurality of irons adapted to iron the crowns of hats carried by said hat blocks, means yieldingly holding each of said irons inwardly toward its respective hat block, and means for determining the angular position of the major and minor axes of each of said hat blocks with relation to the shaft by which it is driven, said means being adjustable for each hat block independently of the others.

7. In a machine of the character described, in combination, a pair of devices for supporting hat blocks, a pair of tools, one adjacent 80 each of said hat blocks and adapted to operate upon a hat carried thereby, means for rotating said hat blocks in the same direction relative to the adjacent tool, a reciprocating member, a mechanism adapted upon actuation to move one of said tools in a path of traverse back and forth across the rotating hat block adjacent thereto, a second mechanism adapted upon actuation to move the other of said tools in a path of traverse back and forth across the surface of the rotating hat block adjacent thereto, a driving connection between said reciprocating member and said first mechanism, and a driving connection between said reciprocating member and 95 said second mechanism, said driving connection being independently adjustable for independently adjusting the loci of the traverses of said two tools.

8. In a machine of the character described, in combination, a centrally disposed driving member, a plurality of shafts for supporting oval hat blocks angularly disposed with respect to said driving member and operatively engaging said driving member at angularly spaced points thereon, a plurality of irons adapted to iron the crowns of hats carried by said hat blocks, one iron being provided for each block and each mounted to be forcefully pressed outwardly from the center of said block by contact with said hat as the latter passes from a side thereof to an end thereof under the iron and to press against said hat with substantially equal force when said hat passes from an end to a side thereof under said iron, and means for adjusting the angular position of each of said hat blocks upon its shaft to balance the composite effect of the outwardly and inwardly acting forces upon said driving member.

9. In a machine of the character described, in combination, a plurality of shafts, a plurality of devices for supporting oval hat blocks, one of said devices being positioned upon each of said shafts to be rotated thereby, a common driving means for rotating said shafts, a plurality of tools adapted to perform work upon the crowns of hats carried by said hat blocks, one tool being provided for each hat block, means yieldingly holding each

of said tools inwardly against a hat carried upon its associated hat block whereby rotation of the hat block is alternately resisted and assisted by the inward thrust of the tool
5 as its position relative to the minor and major axes of the hat block changes, and means for determining the angular positions of the minor and major axes of each of said hat blocks with relation to its shaft, whereby the
10 effect of the thrust of one of said tools upon the action of said driving means will be at all times substantially neutralized by the effect of the thrust of the other tools thereon.

10. In a machine of the character described, in combination, a frame, a plurality of shafts positioned in angular relation to one another and projecting outwardly from said frame for rotatably supporting hat blocks, a plurality of tools, one adjacent to 15 each of said hat blocks, a drive shaft, means driven from said drive shaft adapted to rotate said hat block supporting shafts all in the same direction in relation to the respective tools, a plurality of relatively angularly 20 disposed racks, means adapted to be driven by one of said angularly disposed shafts for reciprocating all of said racks, and a tool support driven by each of said racks adapted to move its respective tool across the surface 25 of a rotating hat block adjacent thereto.

11. In a machine of the character described, in combination, a frame, a pair of outwardly extending shafts rotatably mounted in said frame in end-to-end alignment, an 30 outwardly extending shaft disposed at right angles to said pair of shafts, a driving means positioned in operative relation to the adjacent ends of all of said shafts and connected to rotate all of said shafts, means adjacent 35 the outer end of each of said shafts adapted to support a hat block for rotation by its respective shaft, a plurality of tools for operating upon hats carried by said hat blocks, one of said tools being positioned adjacent 40 the outer end of each of said shafts, an operating means for all of said tools mounted upon the adjacent ends of said pair of shafts and secured to one of said shafts, and means 45 driven by said last means for causing each of said tools to traverse the surface of its respective hat.

In testimony whereof, I have signed my name to this specification this 22nd day of October, 1926.
